Straw cutter

The Schedule referred to in these Letters Patent
and making part of the same, containing a description in the
words of the said Stephen Ulstek, himself of his improvement,
in the Straw cutter, called Stephen Ulstek's Straw cutter

To all to whom these Presents shall come;

Be it known, that I, Stephen Ulstek of
Philadelphia in the county of Philadelphia, state of Penn.
by cranial have invented a new and useful improvement in the
straw cutter, and that the following for cutting straw, hay and
corn stalks called Stephen Ulstek's Straw cutter, and that the
following is a full and exact description of the construction &
operation of the said Machine as invented or improved by me

In the first place I have a frame constructed as
follows - Two posts which I call the front trough posts, are
framed into a base piece, one foot asunder, said base piece
extends beyond the right hand post, and has a post which
I call the first crank post framed into it 6 inch from said
post, the first crank post is framed at top into one end of a
rail, which is framed at its other end into the right hand
trough post above specified - This rail serves as a foundation
for a judge on box of the cranks which is described below. The
other judge on box of the cranks rests on a cap of a post which
I call the second crank post, which is in front of the first one
and connected by two rails one near the bottom of the posts
and the other as far below the top, as to allow the cranks
above specified to work above it - There are two posts which
I call the back trough posts framed into a base of the same
distance asunder as the front trough posts and are connected
above by a rail on which the back end of the trough is
nailed - The back trough posts are framed. Below on one

2 New 1834

8439X

end of two rails which are framed at their other end into front trough posts. The sides of the trough are framed into the front trough posts at one end and nailed at their other end on the inside edges of the back trough posts, the said posts being cut out the thickness of the sides to receive them. The bottom of the trough is in a horizontal position lengthwise. The right hand edge is one inch lower than the left hand one. It extends from the back of the sides of the trough to a fluted cast iron feed roller in front, whose guiders turn in the side of the trough just behind the front trough posts. The top of said roller extends 1 inch above the bottom of the trough. The sides of the trough are tapered from the said feed roller to their back end, to make the trough wider behind than before. This trough is only 2 feet in length. I extend the trough 2 feet back, further by having a separate trough to fit at front to its back, and fastened thereto, by having strips of iron fastened on the top edges at front, which extend over the top of the back trough posts and fit by means of holes in their front ends on iron pins which are permanent in the ends of the posts and by a strip nailed on the back of the first trough at the sides and bottom. The trough is made in two pieces as described above for the purpose of the back part being taken off, when the machine is not in use, so that the machine may then take up but little room. There is an opposing edge fastened on the mouth of the trough, by means of screws, it consists of a bottom and 2 uprights therefrom, the screws are in the uprights. The top of the bottom post of said edge ranges with the top of the feed roller above specified and is of the same height. There is a strip of iron, extending from it to the roller in a descending position, which serves to guide the straw in front of the roller over the opposing edge. There is another feed roller like the above over it. It is in a horizontal position lengthwise and its guiders work in a frame whose uprights work between the front trough posts and strips which are fastened to the sides of the trough. The upright has a rail at top above the roller and one at their bottom which is near

the bottom side rails of the Machine. There are two springs one to each side of the said frame which are fastened at one end to the bottom side rails of the machine their other ends bear on the bottom rail of the roller frame. These springs are to incline the upper roller towards the lower one to compress the straw.

There is a cast iron frame, with short tongues at each corner which slide in cast iron grooves inserted in edges of two rails which are fastened on the front of the machine by means of screws or bolts. Said rails are in an oblique position, and may be more or less oblique, running downwards from the right side of the machine. There is a knife at the back side of said frame, in such a position with it as to be parallel with the top feed roller. The back edge of it comes against shoulders of the frame. Each end of the handleide rests on two screws, which run through the frame. There is one screw at each end of the knife in a counter position with the above and between them. The heads of these are countersunk into the face of the knife. They have taps on their tailends, which bear against the front of the knife frame. The use of the first described screw is to regulate the set of the knife, the knife frame vibrates by means of a crank and pitman. The pitman is connected with the frame by a pivot which is fastened in the lower corner of the latter. There is a balance wheel on the front end of the crank, which has a handle in one of its arms by which the crank is turned. In the downward motion of the knife frame, the knife cuts the straw, when it has nearly returned, the straw is fed by means of a slope knob of the lower end of the frame working against the front end of a horizontal shaft which works in boxes that are screwed to the trough parts of that side of the machine. There being a catch, hung on the inside of said shaft which operates on a ratchet wheel of the bottom roller and once being set in motion, it turns the shaft, which operates on a ratchet wheel of the top roller. The upper catch is also in its ratchet wheel,

The lower one is below the middle rail, it is kept up against it, by the back of a long piece of leather, & upper. The top roller is kept from turning backwards by means of two palls being on the upright of the roller frame operating on the ratchet wheel. The bottom roller is kept from turning back, by two palls being on the guiding strip of the knife frame at that side of the Machine. The upright of the roller frame has a slot in it, which works over the guides of the bottom roller on which the ratchet wheel is. As the knife frame goes down, the catch shaft above described slips forward by means of a half circle spring, whose tail bears against the back bow of the catch shaft, its head is screwed in the lower edge of the shaft. The feed of the rollers is regulated by a flat head screw in the back end of the catch shaft, which slides in a hole of a plate fastened on the trough post. The head of said screw coming against the plate, prevents the catch shaft being pushed too far forward by the spring described above.

There is a board with the grain of the wood perpendicular fastened to the upper rail of the roller frame above described in front of the upper roller, extending to within $\frac{1}{2}$ inch in height of the bottom of the roller. Its face is nearly as far in front as the opposing edge. The use of it is, to prevent the straw from owing on the upward motion of the knife. By the position of the knife with the rollers and the opposing edge and the direction of the knife frames as described above, I get a much greater draw of the knife on the straw, than can otherwise be obtained with a crank of equal length, which makes it cut much easier.

In testimony, that the above is my invention, I have
hereunto affixed my hand, this nineteenth day of September in
the year of our Lord One thousand Eight Hundred and
Thirty two. Witnessed
John D. Smith, Stephen Ulrich
